HENRY C. VAN GIESON, OF PATERSON, NEW JERSEY.

Letters Patent No. 95,957, dated October 19, 1869.

IMPROVEMENT IN BOX-OPENER.

The Schedule referred to in these Letters Patent and making part of the same.

To all whom it may concern:

Be it known that I, HENRY C. VAN GIESON, of Paterson, Passaic county, State of New Jersey, have invented a new Improvement in Box-Openers; and I do hereby declare that the following is a full, clear, and exact description thereof, whereby others skilled in the art may make and use the same, reference being had to the accompanying drawing, forming part of this specification.

This invention relates to a new and useful improvement in an instrument for opening wooden boxes, as, for instance, dry-goods boxes; and consists in hinging a lever to a corner or angle-piece, and combining the same, as hereinafter more fully described.

The accompanying drawing represents the article as when in use, it being a side view, with a box shown in dotted lines.

A is the lever, on which there is a flat chisel-end, B.

C is the corner or angle-piece, which is designed to be of the same width as the part B, and to fit, or nearly fit, the corner of the box.

This angle-piece is hinged to the lever or the chisel-end B, as seen in the drawing, at D.

The part E of the angle-piece C closes up on to B, so that the two form a double chisel-edge, which, in opening the box, is driven under the cover until the part E strikes the box. Then, by bearing down on the lever, the cover is raised, as seen in the drawing.

The parts B E are grooved and tongued, as seen at

g, for preventing injury to the hinge D, when the double chisel is driven in, as before stated, but the hinge may be so constructed as to render this device unnecessary.

The end B of the lever may be split, so as to form a claw, if desired.

By this method of constructing the opener, the cover of a box may be removed without marring the box, and without splitting the covers.

Once driving in of the opener at the corner of the box is sufficient. The opener can be inserted and carried around the box, without driving, after the first corner is raised, and the edge of the box will not be bruised, while the labor is greatly lessened.

Having thus described my invention,

I claim as new, and desire to secure by Letters Patent—

1. A box-opener, provided with an angle-iron, E, to form a rigid fulcrum against the box itself, in the manner described.

2. A box-opener, provided with a recess, g, and corresponding projection on the respective jaws, as and for the purpose specified.

The above specification of my invention signed by me, this 26th day of July, 1869.

HENRY C. VAN GIESON.
